DESIGN FOR A SIGN

Ramsay G. Regester, Philadelphia, Pa., assignor
to Gill Glass & Fixture Company, a corporation
of Delaware

Application October 9, 1935, Serial No. 58,887

Term of patent 7 years

To all whom it may concern:

Be it known that I, Ramsay G. Regester, a citizen of the United States of America and a resident of Philadelphia, in the county of Philadelphia and State of Pennsylvania, have invented a new, original, and ornamental Design for a Sign, of which the following is a specification, reference being had to the accompanying drawing, forming a part thereof.

In the drawing:

Fig. 1 is a front elevational view of the sign showing my new design;

Fig. 2 is a top plan view of the same; and Fig. 3 is an end elevational view of the sign. The sign is characterized by a transparent front face adapted to carry sign characters, and an opaque rear wall.

I claim:

The ornamental design for a sign, substantially as shown and described.

RAMSAY G. REGESTER.
